TUNDISH NOZZLE FOR CONTINUOUS CASTING

This invention relates to the art of continuously casting high melting point metals. It is particularly concerned with a tundish and nozzle adapted for continuously casting steel.

In the continuous casting of high met melting point metals, such as steel, it is desirable to maintain a uniform rate of flow of molten metal into the mold. This is conventionally achieved by casting the steel from a tundish, to which hot metal is added from time to time, so as to maintain a relatively constant ferrostatic head. The amount of metal which the tundish holds is, of course, limited. In the continuous casting of billets and the like of relatively small cross section, it is necessary to supply molten metal at a relatively restricted rate, and this is achieved by using a tundish nozzle of appropriate diameter. In such circumstances when conventional tundish nozzles are used, the molten steel has a tendency to freeze in the nozzle. Any significant impediment in the nozzle reduces the rate of flow of the steel there through, which reduction is deleterious to the continuous casting process. This tendency to freeze is more pronounced in aluminum killed steels than in steels deoxidized with other deoxidizers such as silicon.

In addition past experience with conventional tundish nozzles has shown that during casting of aluminum killed steel the tendency of the steel to freeze in the nozzle is accompanied by a gradual buildup of nonmetallic inclusions consisting mainly of alumina. Depending on the aluminum concentration this buildup can lead eventually to a complete blockage of the tundish nozzle. Again past experience has shown that in view of this reaction it is practically impossible to continuously cast aluminum killed steel successfully through conventional tundish nozzles at aluminum concentrations which are typical for conventionally produced steel of this type (0.015 percent Al. and higher).

It is an object of my invention invention, therefore, to provide a tundish and nozzle so constructed as to reduce the tendency of molten metal to freeze in the nozzle. It is another object to provide a tundish so constructed as to facilitate heat transfer from the molten metal in the tundish to the nozzle and retard heat transfer from the nozzle to the tundish lining. Other objects of my invention will appear from the description thereof which follows.

An embodiment of my invention presently preferred by me is illustrated in the attached figures, to which reference is now made.

FIG. 1 is an elevation in cross section of a tundish of my invention.

FIG. 2 is a detail view to an enlarged scale showing a vertical section through the nozzle of FIG. 1.

The tundish is provided with a steel bottom plate 2 and upright steel sides 3 and 4, which are provided with a refractory lining 5. The bottom plate 2 and lining 5 are formed to provide a vertical cylindrical teeming channel 6, in which is positioned a nozzle 7. A ladle 8 is positioned above tundish 1, from which molten metal is teemed into the tundish as is required.

The structure of the nozzle 7 and refractory lining 5 on the bottom of tundish 1 is more clearly shown in FIG. 2. Immediately adjacent bottom plate 2 is positioned a layer 10 of thermal insulating brick. On top of this layer is positioned a layer 11 of conventional refractory brick. This layer 11 constitutes the working lining. Layers 10 and 11 together make up the tundish lining 5. Around cylindrical channel 6, layer 11 is stepped back from layer 10, so as to provide an annular ledge 12, which supports nozzle 7.

Nozzle 7 comprises an annular base portion 13 which supports a frustoconical nozzle block 16. Base portion 13 is made of thermal insulating brick and is dimensioned to be supported on ledge 12. The top surface 14 of base 13 is a portion of a sphere and does not extend above the upper face of layer 11 of lining 5. The central opening 15 in base 13 has a bottom diameter somewhat less than that of channel 6 and tapers to a still smaller diameter at its upper end.

Frustoconical nozzle block 16 has a central bore 17 of the desired nozzle diameter. This diameter is smaller than that of

the upper end of central opening 15. The lower surface of block 16 matches the spherical upper surface 14 of base portion 13. Nozzle block 16 projects well above the upper surface of refractory layer 11, so that most of its external surface is in contact with the molten metal in the tundish 1. The gap between its lower outer edge or skirt 18 and layer 11 is filled with a plastic refractory cement 19. Nozzle block 16 is made of a refractory material having a high thermal conductivity.

In operation tundish 1 is filled to the desired height with molten metal, such as steel, from ladle 8. The steel immediately begins to flow out of tundish 1 through bore 17 of nozzle block 16 at a rate determined by the diameter of that bore and at a height of the steel in the tundish. As the molten steel is in contact both with the inside and outside surfaces of nozzle block 16, which is made of high thermal conductivity refractory material, the temperature of block 16 tends to approach that of the molten steel. While momentary chilling of steel may occur around the outside of the relatively small volume of steel passing through bore 17, it does not occur around the outside surface of block 16, which is in contact with a much larger volume of steel, but on the contrary, heat will flow from the molten steel through the outside surface of the high thermal conductivity nozzle block 16 toward the bore 17, so as to raise the temperature around the inside of that bore. As the base portion 13 is made of thermal insulating refractory material, heat flow away from bore 17 through the base of nozzle block 16 will be retarded.

The fire clay compositions, which are conventionally used for the refractories of layer 11 of the tundish lining, have a thermal conductivity range from about 8 to 12 B.t.u.'s per hour per square foot per degree F. per inch at temperatures in the neighborhood of 2000° F. For nozzle block 16 I prefer to use a refractory having a thermal conductivity at that temperature not less than that of zircon, which has a thermal conductivity of about 17 in the units above mentioned. I have used materials having a thermal conductivity as high as 20 with excellent results and do not envisage any upper limit to the thermal conductivity of my nozzle block 16. For comparison, the insulating brick used in layer 10 has a thermal conductivity of about 2.

Although I have described and illustrated apparatus embodying a composite nozzle structure which is made up as a unit and fitted into the tundish bottom, my invention also comprehends embodiments in which the heat insulating material on the tundish bottom extends upwardly in the nozzle area within the working lining, and supports the high heat conductivity nozzle block.

I claim:

1. In a tundish for teeming molten steel including a refractory working lining and a teeming nozzle, the improvement comprising a lining of heat insulating material positioned below the refractory working lining at least in the area surrounding the teeming nozzle and extending up into the refractory working lining in the area of the teeming nozzle, a nozzle block of heat conductive refractory material having a bore which defines the cross section of the stream of molten steel teemed therefrom, and being positioned so that at least the major portion of the bore is above the upper surface of the refractory working lining, whereby heat is transferred to the nozzle block from the molten steel sufficient to retard solidification of molten steel in the bore, the nozzle block being spaced from the refractory working lining by the heat insulating lining extending up into the refractory working lining.

2. The apparatus of claim 1 in which the heat insulating lining extends up into the refractory working lining to about the upper surface thereof.

3. The apparatus of claim 1 in which the heat insulating lining extending up into the refractory working lining is of substantially hemispherical shape, the top of the hemisphere being not higher than the upper surface of the refractory lining, and the nozzle block has a bottom surface complementary to that hemispherical shape.

4. The apparatus of claim 1 in which the heat conductive refractory material has a heat conductivity as at least as great as zircon.

5. The apparatus of claim 1 in which the heat insulating

material extending up into the refractory working lining in the area of the teeming nozzle and the nozzle block are formed as a unit which fits into the tundish bottom.
